UNITED STATES PATENT OFFICE

1,926,670

ELBOW

Fred C. Fantz, Webster Groves, Mo.

Application June 11, 1932. Serial No. 616,606

2 Claims. (Cl. 285—108)

In Patent No. 1,752,331 I have shown a return bend for oil stills and the like in which the joints are subjected not only to high pressure but also to high temperatures; also an elbow in Figs. 5 to 7 inclusive. In devices of this type it is highly desirable to have a joint between the fitting and the tube which will not interfere with the flow of the fluid and also which will not coke so as to render its removal difficult or slow for it is well known to persons familiar with the art that the refinery regards the expense caused by a shut down as much more serious than the cost of the new equipment expensive though it may be.

My invention has for its object to provide an elbow which will possess the advantage of being quickly and easily removed so as to permit inspection of the tubes as well as the insertion of tube cleaner in the tubes.

A further object being to provide an uninterrupted interior surface in the elbow and tube so as not to interfere with the flow of the fluid therethrough.

My means of accomplishing the foregoing objects may be more readily understood by having reference to the accompanying drawings, in which—

Fig. 1 is a side elevation of an elbow embodying my improvements having the joint on one face only, a portion being broken away to show the interior construction;

Fig. 2 is a plan view of the same;

Fig. 3 is an end view of the same;

Fig. 4 is a side elevation partly in section of an elbow embodying my invention having my improved joint at both faces;

Fig. 5 is a top or plan view thereof; and

Fig. 6 is an end view of the tube being omitted. Similar reference numerals refer to similar parts throughout the entire description.

As shown in Figs. 1 to 3 inclusive the elbow generally formed of some noncorrosive alloy is provided with an annular groove 1 in one of its faces 2. This groove is adapted to receive the end 3 of a tube 4 which is convex in cross section. Preferably this is a ground joint which I have found in practice to be highly satisfactory. The tube 4 is preferably formed with an external shoulder 5 which engaged by a sectional bushing or ring 6 preferably formed of steel. This bushing or ring 6 fits into an annular portion 7 of a housing which comprises upwardly extending side walls 8 and 9 preferably segmental in cross section. Arcuate slots 10 and 11 are cut or formed in these side walls adjacent their upper ends. In these slots 10 and 11 I mount a plate 12 which has a

set screw 13 in a centrally located, threaded, aperture. The end of the screw 13 contacts an abutment 14 formed on the exterior wall of the elbow. The other face 15 of the elbow is provided with a flange 16 for conveniently securing it to a flanged pipe (not shown).

To assemble the device the annular portion 7 is first passed over the end of the tube 4 then the sectional bushing or ring 6 is placed between the external surface of the tube wall and the internal shouldered surface of the annular member 7. The elbow is then placed in the housing so that the groove 1 in its face 2 will register with the end 3 of the tube 4. The plate 12 is then fitted into the arcuate slots 10 and 11 and by tightening the set screw 13 the end 3 of the tube 4 will be drawn into the groove 1 and a tight joint will be made which practice has shown is sufficiently rugged in character to withstand, without leakage, the tremendous pressures and temperatures to which these joints are subjected to when in commercial use. It will also be seen that this construction gives a direct pull upon the shoulder on the tube 4.

As shown in Fig. 4 each of the two faces 2 of the elbow are provided with a groove adapted to receive the ends of tubes where a ground joint is desired for both openings. In this form the housing is constructed differently than in the form previously described and a second pair of slots 20 and 21 are provided in the housing walls above this face of the elbow in which I mount a plate 22 having a set screw 23 therein the end of which contacts an abutment 24 formed upon the external wall of the elbow. I have found in practice when thus constructed it is desirable in some cases to have some play between the bushing or ring and the annular portion accordingly I provide an annular space 25 for this purpose.

Having described my invention what I regard as new and desire to secure by Letters Patent is:

1. The combination with an elbow, having annular grooves in each face, adapted to connect a plurality of tubes, the ends of which fit said grooves, each tube having a shoulder, of a housing therefor, having annular portions, sectional bushings mounted intermediate the tubes and said annular portion, adapted to engage the shoulders on the tubes, detachable means mounted in said housing, and means mounted in said means which contact said elbow, said bushing being spaced from said annular members.

2. In a device of the character described, the combination, with a housing having annular

members adapted to encircle and engage the ends of a pair of tubes, of sectional metal bushings, loosely mounted intermediate said annular members and said tubes, side walls on said annular members, an elbow mounted inside of said side walls, means detachably mounted in engagement

with said side walls, and set screws mounted in said means, which engage said elbow whereby the tightening of said set screws will draw and hold the ends of said tubes and the faces of said elbow tightly together.
